Henry Forster, Broadview, Ill.

Application May 12, 1945, Serial No. 119,527

Term of patent 14 years

(Cl. D71—1)

To all whom it may concern:

Be it known that I, Henry Forster, a citizen of the United States, residing at Broadview, in the county of Cook and State of Illinois, have invented a new, original, and ornamental Design for an Internal Combustion Engine Unit, of which the following is a specification, reference being had to the accompanying drawing, forming part thereof.

Fig. 1 is a front elevational view of an internal

combustion engine unit embodying my new design.

Fig. 2 is a side elevational view of the same.

Fig. 3 is a rear elevational view of the same.

Fig. 4 is a side elevational view of the same.

Fig. 5 is a top plan view.

I claim:

The ornamental design for an internal combustion engine unit, substantially as shown.

HENRY FORSTER.
